UNITED STATES PATENT OFFICE.

WILLIAM A. DUNN, OF DULUTH, MINNESOTA, ASSIGNOR OF ONE-HALF TO A. M. MILLER, JR., OF DULUTH, MINNESOTA.

WEAR-COMPENSATING BEARING.

1,109,049.

Specification of Letters Patent.

Patented Sept. 1, 1914.

Original application filed November 5, 1910, Serial No. 590,919. Divided and this application filed February 2, 1912, Serial No. 674,934. Renewed February 7, 1914. Serial No. 817,327.

To all whom it may concern:

Be it known that I, WILLIAM A. DUNN, a citizen of the United States, residing at Duluth, in the county of St. Louis and 5 State of Minnesota, have invented certain new and useful Improvements in Wear-Compensating Bearings, of which the following is a specification.

This invention relates to improvements 10 in means for imparting lateral pressure to the outer surfaces of beams when passing through a mill, and particularly to the construction of the mounting of the vertical roller.

15 In my co-pending application for patent, Serial No. 590,919, I have shown and described a rolling mill, with which my present invention cooperates, and from which this application is divided.

20 The object of the invention is to provide means for supporting a vertical roll adjacent the ends of the flange controlling or web reducing rolls, whereby the journal of the roll may be circumferentially adjusted 25 to obtain a uniform bearing, and thereby prolong the life of the parts.

A further object of the invention is to provide special means for vertically adjusting the journal to take up wear.

30 Another object of the invention is to provide means for cooling the bearing and the vertical roll during the operation of the mill.

35 My invention also aims to provide improved means for supporting the journal of the vertical roll.

The invention also comprehends improvements in the specific details of construction and arrangement of parts, which will be 40 hereinafter described, and particularly pointed out in the claims.

In the drawings:—Figure 1 is a vertical section of my improvement. Fig. 2 is a side elevation of the bearing and side roll. Fig. 45 3 is a face view of the same, the web reducing rolls of the mill being shown in dotted lines. Fig. 4 is a plan view.

The numeral 1 indicates upper and lower web reducing rolls, such as disclosed in my 50 before mentioned patent.

Mounted on a frame and extending therefrom is an auxiliary frame 4, formed with guideways 5. Slidably mounted in the guideways 5, is a bearing 6, of special construction. This bearing comprises a lower section 7, and an upper section 8, in which

the journals of the vertical roll are supported.

The lower bearing section is formed with a bottom 9, an end wall 10, two side walls 11—11, and is open at its inner end. Formed in the bottom is an opening 13, to provide one of the bearings for the vertical journal on which the roll revolves, and spaced from the opening and concentric therewith is a well 15, into which enter vertical bolts 16. On the outer surfaces of the side walls 11—11 are ribs 17, which fit in the guideways 5—5 in the auxiliary frame 4.

The upper section 8, comprises a plate 70 formed with a depending flange 18, above which and extending above same is a lateral flange 19, and centrally of said section and in alinement with the opening 13, in section 7, is an opening 20, having a notch 20^a, 75 in the wall thereof. This opening forms one of the bearings for the end of the journal. The flange 18 engages the inner surface of a flange 21, on the lower section 7, while the flange 19, engages the upper surface of 80 said lower section.

Spaced from the opening 20, and concentric therewith, is a well or depression 24, which is in vertical alinement with the well 15, and communicating therewith is an opening 25, having a plug 26, whereby to afford 85 means for introducing a lubricant.

The upper section is bolted to the lower section as indicated at 27, to form a rigid and substantial structure when the parts 90 are assembled.

Mounted in the bearings 13 and 20, is a hollow journal 29, formed with a central enlarged portion 30, and two end trunnions 31—31. The upper trunnion 31, is 95 formed with a square opening 31^a, to receive a tool, by means of which the journal may be rotated in its bearings. The periphery of the upper trunnion is formed with a series of vertical slots 32, which may be brought 100 into registry with the slot 20^a in the wall of the opening 20. When one of these slots is brought into registry with the slot 20^a, a key 35, is inserted to form a lock between the journal and the bearing, whereby the 105 journal is held stationary.

Fitting around the central enlarged portion of the journal is a tapered bushing 36, keyed to the journal as indicated at 37. The bushing is in alinement with the wells 110 15 and 24, and is supported on the vertical screws 16.

Mounted to rotate on the tapered bushing is a vertical roll 39, the upper and lower faces of which bear against the upper and lower sections of the bearing. This roll is 5 free to rotate when frictionally engaged by a beam passing through the mill.

The bearing as a whole is adjusted toward and from the web controlling rolls by a swiveled screw or screws 40, as fully set 10 forth in my before mentioned patent.

In operation, the parts as assembled as described, and when a beam is passing through the mill, as shown in Fig. 1, the vertical roll is forced toward the web reducing rolls and flattens the flange. The strain 15 incident to this action is severe, and it is the purpose of this invention to distribute this strain throughout the entire structure. When the vertical roll is in contact with the beam, the outward thrust is against the walls of the openings 13 and 20, and because of the peculiar arrangement of parts, I am 20 enabled to make the trunnions of substantial diameter to afford sufficient frictional surface in the bearings to take the excessive 25 thrust so that it will be properly distributed. Hence the strain at the top comes on the top section 8, and because of the flange 18, it is transmitted to the upper part of 30 the lower section. The strain at the lower trunnion is transmitted to the lower section 7, and as both points of the greatest strain 35 are on the opposite sides of the plane of the screw 40, obviously the thrust is centralized on said screws.

In order to prevent the bushing wearing at one point, the key 35 is withdrawn, and a tool is inserted in the square opening 31^a, and the journal and bushing are rotated so as 40 to bring another one of the slots 32, into registry with the slot 20^a, and then the key is again inserted. By this means, the entire 45 peripheries of the bushing and the trunnions may at different times be used, and thereby I am enabled to prolong the life of these parts, and I am also enabled to maintain a smooth bearing for the roll 39.

To compensate for the wear of the bushing, the latter is made tapering and is vertically 50 adjusted by the screws 16. By turning the screws against the bottom of the bushing 36, the latter is forced up until the proper adjustment is secured. It is because of this adjustment, and the fact that the 55 bushing must be of greater length than the enlarged portion of the journal, that I have provided the wells 15 and 24, in the sections 7 and 8. By this means, the roll 39 will at all times have a bearing from top to bottom.

During the time the mill is in operation, 60 water passes through a pipe 40, and the hollow journal, and flows through the opening over the top of the bearing and the vertical 65 roll and serves to cool the entire structure.

This feature is quite essential, not only because of the heat from the beam, but because of the great friction between the parts, which would in the absence of the water, heat the face of the vertical roll and damage it. If the periphery of the roll is marred, 70 it will produce a rough surface on the face of the flange of the beam, and it is my purpose, by the construction described, to avoid this difficulty. 75

Water must be supplied to all the rolls, not only to cool the parts but to wash the scales of the beam from said rolls when the mill is in operation.

What I claim is:

1. In combination, a frame, a hub having upper and lower shoulders and mounted in the frame, the shoulders engaging the inner surfaces of the frame and confined therebetween, a tapered bushing slidably mounted on the hub, a spline between the hub and bushing, means for sliding the bushing upward including adjusting devices on which said bushing is supported, the bushing being normally seated on said devices by gravity, a rotary element mounted on the bushing and supported on the frame, means for permitting circumferential movement of the hub and bushing to take up wear of the rotary element, and means at the top of the hub and the frame for locking the hub in position. 85

2. In combination, a frame comprising a section having one end open and a coöperating section having a depending flange 100 which engages the inner surfaces of the first mentioned section, the said sections having aligned openings, means for securing the sections together, a hub having a central bearing portion and provided at its ends with reduced trunnions which fit in the openings in the sections, the shoulders adjacent the trunnions bearing against and being confined between the upper and lower surfaces of the frame, a tapered bushing fitted over 110 the central bearing portion of the hub, a rotatable element mounted on the bushing and confined at its upper and lower ends between the sections, means for vertically adjusting the tapered bushing, and means 115 coöperating with one of the trunnions for locking the hub in the frame.

3. In combination, a frame formed with aligned openings, the walls of one of said openings having a slot, a hub having a central bearing portion and end trunnions, the latter fitting in the aligned openings, a bushing splined on the central bearing portion one of said trunnions having a slot adapted to register with the slot in the opening in 125 the frame, a key fitting in the registering slots to lock the hub in position and means for vertically adjusting the bushing, and a rotatable element supported on the bushing. 130

4. In combination, a frame formed with

alined openings and adjacent wells, a hub mounted in the alined openings, means including a key and slots between the hub and the casing for locking the hub against rotation, a tapered bushing splined on the hub and adjustable in alinement with the wells, means in the bottom of the bearing for vertically adjusting the tapered bushing, and a rotatable element mounted to rotate on the 10 tapered bushing.

5. In combination, a frame formed with alined openings, a hollow hub mounted in the openings and open at its upper end, means between the hub and the bearing for locking said hub against rotation, a tapered bushing splined on the hub, means for vertically adjusting and supporting the tapered bushing, and a rotatable element freely rotatable on the tapered bushing.

15 6. In combination, a frame comprising a lower section provided with vertical flanges and open at one end, and formed with a circular well, a top section formed with flanges which fit in and over the upper edge of the 20 lower section, said upper section having an opening and a well in alinement with the opening and well of the lower section, a hollow hub open at its upper end and formed with a central bearing portion and end 25 trunnions, the trunnions fitting in the openings of the upper and lower sections, there

being a series of slots formed between one of the trunnions and the walls of one of the openings, a key fitting in the registering slots to lock the hub against rotation, a 35 bushing splined on the central bearing portion of the hub, said bushing being in alinement with the wells, and means for adjusting the tapered bushing.

7. In combination, a frame formed with 40 alined openings, a hub having opposite end trunnions which fit in the alined openings, there being registering slots between one of the trunnions and the wall of one of the alined openings, a key fitting in the slots, a 45 tapered bushing slidably fitted on the hub, a spline between the tapered bushing and the journal, adjusting screws in the casing to engage with the tapered bushing to adjust the position of same on the hub, said screws 50 serving as a support for the tapered bushing, the tapered bushing and the hub being rotatable when the key is removed, and a rotating element mounted on the tapered bushing. 55

In testimony whereof I affix my signature in presence of two witnesses.

WILLIAM A. DUNN.
